CLAIM

We claim the ornamental design for a safety vest with light tubes, as shown and described.

DESCRIPTION

FIG. 1 is a perspective view of the rear of a safety vest with light tubes, showing our new design;

FIG. 2 is a perspective view of the rear of the safety vest with light tubes from an upper angle;

FIG. 3 is a front view of the safety vest with light tubes;

FIG. 4 is a rear view of the safety vest with light tubes;

FIG. 5 is a side elevation view of the safety vest with light tubes from the left side;

FIG. 6 is a side elevation view of the safety vest with light tubes from the right side; and,

FIG. 7 is a perspective view of the front of the safety vest with light tubes from a lower angle.

The broken lines in FIG. 1 depicting a wearer represents environmental subject matter that forms no part of the claimed design. The remaining broken lines in the figures, including lines of stitching, depict portions of the safety vest with light tubes that form no part of the claimed design.

1 Claim, 7 Drawing Sheets
